UNITED STATES PATENT OFFICE.

OTTO W. MEISSNER, OF CHICAGO, ILLINOIS, ASSIGNOR TO RODGER
BALLAST CAR COMPANY, OF COOK COUNTY, ILLINOIS, A CORPORA-
TION OF ILLINOIS.

DUMP-CAR.

SPECIFICATION forming part of Letters Patent No. 768,535, dated August 23, 1904.

Application filed July 27, 1903. Serial No. 167,151. (No model.)

To all whom it may concern:

Be it known that I, OTTO W. MEISSNER, a citizen of the United States, residing at Chicago, in the county of Cook and State of Illinois, have invented certain new and useful Improvements in Dump-Cars, of which the following is a specification.

This invention relates to that class of dump-cars known as "center-dump" cars, and has for its principal object the providing of a simple, economical, and efficient dumping-car which will discharge loose bulky freight at either or both sides and center, as will more fully hereinafter appear.

The invention consists principally in a dump-car in which there are combined a supporting-framework having upwardly-extending side and end boards and a dumping bottom portion formed of a central V-shaped portion extending lengthwise of the car and underneath the supporting-frame and two swinging portions pivotally secured to the framework of the car to each side of the V-shaped dumping portion and arranged to lie in a flat plane and form flat floor-sections when carrying a load and be swung downwardly to discharge a portion of the load to each side of the car.

The invention consists, further and finally, in the features, combinations, and details of construction hereinafter described and claimed.

In the accompanying drawing, the figure represents a transverse sectional elevation of one type of car as it appears when constructed in accordance with these improvements.

In illustrating and describing these improvements I have only illustrated and will describe that which I consider to be new, taken in connection with so much that is old as will properly disclose the invention to others and enable those skilled in the art to practice the same, leaving out of consideration other and well-known elements which if set forth herein would only tend to confusion, prolixity, and ambiguity.

In constructing a car in accordance with these improvements I provide a supporting-framework formed in any desired way, but

preferably as shown in the drawing, in which there is a plurality of transverse deck-beams 50 a. Extending upwardly from the supporting-framework of the car are side boards b and end boards c, secured thereto in any desirable or convenient manner.

To provide a dumping-car which can be used for the purpose of discharging a load entirely between the track-rails in a manner similar to the well-known Rodger type of car or which can be used for discharging a portion of the load to one or both sides of the track or for discharging the entire load between and to both sides of the track, as may be necessary, a centrally-disposed V-shaped hopper portion is provided, extending lengthwise of the car, with its apex extending below the supporting-frame. This V-shaped hopper portion is made of one inclined side d, rigidly secured to the framework of the car, and a swinging inclined side e, which may be used as a discharging-door to dump material between the track-rails. 70 To complete the dumping-bottom, two swinging sections f and g are provided and pivotally secured at their inner lateral edges to the supporting-framework of the car at each side of its longitudinal center and also at each 75 side of the central dumping hopper portion. These swinging sections may be used, as shown to the left of the figure, as flat bottom portions to carry a portion of any desired load, or they may be dropped down, as shown to the right of the figure, so as to discharge a portion of the load independently or simultaneously to either or both sides of the track and in connection with the hopper portion all of the load between the rails, all of which 85 will be understood and appreciated by those skilled in the art. To open and close these swinging sections which form the flat bottom, rock-shafts f and chain mechanism i are provided and mounted as shown in the drawings, 90 so that the rotation of such shaft in one direction tends to close the doors, while a rotation in the opposite direction permits them to be opened. To open and close the swinging door of the hopper portion, another rock-shaft j is provided, having chain mechanism

80

k wound therearound and secured to hooks *l* on the lower free edges of such swinging door, the operations of which are well known to those skilled in this particular art.

5 I claim—

1. In a dump-car of the class described, the combination of a supporting-framework having upwardly-extending side and end boards, and a dumping bottom portion formed of a central **V**-shaped portion extending lengthwise of the car and underneath the supporting-frame and two swinging sections pivotally secured to the framework of the car to each side of the **V**-shaped dumping portion and arranged 10 to lie in a flat plane and form flat floor portions and to be swung downwardly to discharge a portion of the load, substantially as described.
2. In a dump-car of the class described, the combination of a supporting-framework provided with upwardly-extending side and end boards, and a dumping bottom portion formed 15 of a central **V**-shaped hopper portion extending lengthwise of the car below the supporting-frame and two swinging sections pivot-

ally secured to the supporting-framework of 25 the car to each side of the hopper portion so as to form a flat bottom and dumping sections, substantially as described.

3. In a dump-car of the class described, the combination of a supporting-framework provided with upwardly-extending side and end boards, and a dumping bottom portion formed 30 of a centrally-located **V**-shaped hopper portion extending lengthwise of the car and having one fixed inclined side and one swinging 35 side forming a discharging-door and two swinging sections pivotally secured at their inner edges to the supporting-framework of the car at each side of its longitudinal center and outside of the **V**-shaped hopper portion 40 so as to form flat floor portions for carrying a load and inclined portions to discharge a portion of the load to each side of the car, substantially as described.

OTTO W. MEISSNER.
